Primary Examiner — Jennifer Rivard(74) *Attorney, Agent, or Firm* — Joanne N. Pappas; Kevin C. Johnson(57) **CLAIM**

The ornamental design for a razor, as shown and described.

DESCRIPTION

FIG. 1 is a front perspective view of a design of a razor of the present invention;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is rear perspective view thereof.

The broken line disclosure illustrates portions of the razor and forms no part of the claimed design.
